The ornamental design for a multi-purpose tool, as shown and described.

DESCRIPTION

FIG. 1 is a perspective view of a multi-purpose tool, showing our new design;

FIG. 2 is a side view of the multi-purpose tool;

FIG. 3 is an alternate side view of the multi-purpose tool;

FIG. 4 is a front view of the multi-purpose tool;

FIG. 5 is a rear view of the multi-purpose tool;

FIG. 6 is a top view of the multi-purpose tool; and,

FIG. 7 is a bottom view of the multi-purpose tool.

The broken lines in the drawings illustrate features of the multi-purpose tool that form no part of the claim.
